INTERNAL COMBUSTION ENGINE

Stanley E. Cliff, Napa, Calif.

Application May 4, 1942, Serial No. 441,692

4 Claims. (Cl. 123—51)

The present invention relates to new and useful improvements in internal combustion engines of a type in which the cylinders are arranged in the form of a square comprising a plurality of polygonal sets of cylinders disposed in side-by-side relation and defining a polyhedron with the crankshafts of the pistons operated in the cylinders located at the corners of adjacent cylinders and the invention has for its primary object to provide cylinder blocks of duplicate construction with a pair of the cylinders arranged in opposed relation at each side of the engine and providing a spacing block between the adjacent ends of the cylinder blocks and within which the valves for the intake and exhaust ports of the engine are positioned as well as the spark plugs, or other forms of ignition for the explosive charge.

A further important object of the present invention is to provide means for operatively connecting each of the crankshafts at the four corners of the engine and for connecting the valve-operating cam shafts for synchronous actuation to equalize distribution of the power strokes of the several cylinders.

A still further object is to provide an engine of this character of simple and practical construction, which is efficient and reliable in performance, relatively inexpensive to manufacture, and maintain in operation, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout and in which—

Figure 1 is a longitudinal sectional view through the assembled engine cylinders.

Figure 2 is an end elevational view.

Figure 3 is a side elevational view of one side of the engine.

Figure 4 is a sectional view through one of the engine cylinders taken substantially on a line 4—4 of Figure 1.

Figure 5 is a sectional view through one of the spacing blocks for a pair of the cylinders taken substantially on a line 5—5 of Figure 1.

Figure 6 is a fragmentary longitudinal sectional view of one of the crankshafts taken substantially on a line 6—6 of Figure 1.

Figure 7 is a longitudinal sectional view of one of the cylinders removed from the engine.

Figure 8 is a perspective view of one of the cylinder linings.

Figure 9 is a fragmentary view in elevation of one side of the engine, and

Figure 10 is a side elevational view of one of the cylinders.

Referring now to the drawings in detail, wherein for the purpose of illustration I have disclosed a preferred embodiment of the invention, the numeral 5 designates one of the engine cylinders of which there are eight employed in constructing a complete engine unit arranged in the form of a square as shown to advantage in Figure 1 of the drawings, a pair of the cylinders being disposed at each side of the square in opposed relation, and if desired two or more complete engine units may be connected in side-by-side relation as shown in Figure 2 of the drawings.

The opposed ends of the cylinders are formed 20 with flanges 6 between which is positioned a spacing block 7 and connected thereto by bolts 8. Inwardly projecting shoulders 9 are formed adjacent each end of the cylinders against which is fitted a cylinder lining 10 to form a water jacket 11 between the walls of the cylinder and the lining.

The adjacent ends of the linings 10 have flanges 12 adapted to overlie the adjacent shoulders of the cylinders and the linings are held 30 in position by the spacing block 7, the spacing block 7 having a bore 13 in alignment with the adjacent cylinders.

A piston 14 is provided with a working fit in each of the cylinder linings 10, each piston having a piston rod 15 connected thereto in the usual manner and attached to a crankshaft 16 by means of a bearing 17.

The ends of the cylinder blocks at the corners of the engine are flared out into curved walls to 40 form a crankcase 18 connected together by means of flanges 19, the shaft 16 having its ends journaled in the opposite sides of the crankcase.

Each of the crankshafts is formed with opposed cranks 20 for connecting the piston rod 15 of adjacent engine units at adjacent sides of the engine, the pistons connected to said crankshafts thus having opposite power and suction strokes.

The outer ends of the crankshaft 16 are also 50 journaled in bearings 21 disposed outwardly of the crank cases and the bearings 21 at each side of the engine are connected by tie rods 22. The crankshafts 16, at the respective corners of the engine, are connected for synchronous operation 55 by means of gears 23, preferably of the herring

bone type, connected to the respective crankshafts, each of the gears 23 being engaged by a gear 24 secured on a cam shaft 25 and the gears 24 are engaged by a central idler gear 26 mounted on a shaft 27. The shafts 25 and 27 are supported in arms 28 connected to one side of each pair of the engine cylinders.

Each of the cam shafts 25 is also provided with cams 29 arranged for operating a valve push rod 30 journaled in guides 31 at the sides of the cylinder blocks, the push rods being arranged for actuating rockers 32 pivoted on brackets 33 for actuating the valves 34 mounted in the spacing blocks 7 for controlling the intake and discharge ports 35 and 36 formed in the spacing blocks and communicating with the combustion chambers 13 between the opposed ends of the cylinders blocks.

The engine is designed for using either gasoline or Diesel fuel and when using Diesel fuel the spacing blocks 7 are provided with a fuel injector 37 of conventional construction and when the engine uses gasoline as the fuel, a spark plug (not shown) is substituted in place of the injector 37.

Each of the crankcases 18 is provided with a cleanout and repair opening 38 having a cover 39 secured in position thereon by means of the bolts 40.

Having described the invention what is claimed as new is:

1. An internal combustion engine comprising a plurality of cylinders arranged in end to end relation to form a square, each side of the square being composed of a pair of cylinders, a spacing block between each of said pairs of cylinders and connecting one end of the cylinders, an enlarged casing segment at the other end of each cylinder connected together at the corners of the square bank of cylinders to form a crankcase at each corner, a piston working in each cylinder, crankshafts journaled in the crank-cases and operatively connected to the pistons, intake and exhaust ports in the spacing blocks, valves controlling said ports, and gears connecting the crank-shafts for synchronous operation of the several pistons.

2. An internal combustion engine comprising a plurality of cylinders arranged in end to end relation to form a square, each side of the square

being composed of a pair of cylinders, a spacing block between each of said pairs of cylinders and connecting one end of the cylinders, an enlarged casing segment at the other end of each cylinder connected together at the corners of the square bank of cylinders to form a crankcase at each corner, a piston working in each cylinder, crankshafts journaled in the crank-cases and operatively connected to the pistons, intake and exhaust ports in the spacing blocks, valves controlling said ports, cam shafts for operating the valves, gears connecting the cam shafts with the crankshafts, and gears connecting the cam shafts and crankshafts for synchronous operation.

5 3. An internal combustion engine comprising a plurality of cylinders arranged in end to end relation to form a square, each side of the square being composed of a pair of cylinders, a spacing block between each of said pairs of cylinders and connecting one end of the cylinders, an enlarged casing segment at the other end of each cylinder connected together at the corners of the square bank of cylinders to form a crankcase at each corner, a piston working in each cylinder, crankshafts journaled in the crank cases and operatively connected to the pistons, intake and exhaust ports in the spacing blocks, valves controlling said ports, cam shafts for operating the valves, gears connecting the cam shafts with the crankshafts, and gears connecting the cam shafts and crankshafts for synchronous operation.

10 15 20 25 30 35 40 45 4. An internal combustion engine comprising a plurality of cylinders arranged in end to end relation to form a square, each side of the square being composed of a pair of cylinders, and each cylinder including a crankcase segment at one end adapted for attaching to the segment of an adjacent cylinder to form a crank case at each corner of the engine, an internal shoulder at the other end of each cylinder, a liner in the cylinder having a flange seated on the shoulder, and a spacing block interposed between each pair of cylinders and having a bore communicating with the cylinders, said spacing block having intake and discharge ports communicating with adjacent cylinders.

STANLEY E. CLIFF.
